UNITED STATES PATENT OFFICE.

PAUL RISSMAN, OF DETROIT, MICHIGAN.

STAPLE MAKING AND DRIVING TOOL.

Application filed December 5, 1921. Serial No. 520,027.

To all whom it may concern:

Be it known that I, PAUL RISSMAN, a citizen of the United States, and residing at Detroit, in the county of Wayne and State of Michigan, have invented a new and Improved Staple Making and Driving Tool, of which the following is a specification.

This invention relates to portable means for forming fastening devices, particularly staples, from wire and for driving them immediately after being made, and its object is to provide a structure of this character which shall be so small and light that it can be moved about and manipulated with one hand, leaving the other free for other purposes, which shall be simple in construction, which shall carry its own supply of wire, and which can be driven by a flexible shaft connected to a stationary motor of any desired type.

This invention consists of a staple forming and driving device embodying a case which can be carried about in one hand, a wire-holding spool mounted on the case and means to feed the wire to a staple former, a staple forming device and a staple driving device, and means for actuating the wire feeding, staple forming and staple driving mechanism.

It further consists in a main driving shaft for actuating the staple forming and driving mechanisms, a constantly running flexible shaft, a trigger controlled device whereby a connection between the two shafts is made, and means to disconnect the shafts after each staple is driven.

It also consists in the details of construction illustrated in the accompanying drawings and particularly set forth in the claims.

In the accompanying drawings, Fig. 1 is a side elevation, Fig. 2 is a front elevation, and Fig. 3 is a plan of this novel staple forming and driving machine. Fig. 4 is a central vertical section thereof. Fig. 5 is a view showing the feed rolls in section and the main portion of the case in elevation. Fig. 6 is a plan of a staple. Figs. 6 to 12 inclusive are sections on the lines 6-6 to 12-12 inclusive respectively of Fig. 4. Fig. 13 is a perspective of the staple-bending dog. Fig. 14 is a plan of the movable portion of the staple shear and bender. Fig. 15 is a plan of the staple driver or hammer.

Similar reference characters refer to like parts throughout the several views.

The case of this tool is formed of two

parts 1 and 2 secured together by means of screws 3. The mechanism is driven in any desired manner but I have shown a flexible shaft which is connected to the internal mechanism as follows. A flange 4 at the bottom of the part 1 is bored to receive a bushing 5 (Fig. 4) held in position by a nut 6. In this bushing is rotatably mounted a short sleeve 7 having a central hole in which a pin 8 is secured. A flexible sheath 9 has a thimble 10 in its end which is held against the sleeve 7 by a nut 12. The flexible shaft 13 is halved as is the pin 8 and held matched with this pin within the sleeve 7. On the sleeve is a pinion 14 and the main shaft 26 has a reduced end which extends into this sleeve 7 and also supports a sleeve which embodies a gear 16 and a clutch member 18 and is loose on the main shaft. If desired, the parts 8 and 13 may be integral.

A second bushing 19 is secured in the flange 4 and constitutes the bearing for the short shaft 20 which carries the gear 21 and pinion 22 and is held in position by the screw 23. The gear 21 meshes with the pinion 14 and the pinion 22 with the gear 16 so that by these devices the clutch member 18 is driven by the shaft 13 but at a very reduced rate.

A pair of lugs 24 on either part of the case carry a bearing sleeve 25 in which the main shaft 26 is mounted and which makes one revolution for each cycle of the machine. A head 27 on the lower end of this shaft has fingers 28 adapted to fit in grooves 29 in the sleeve 30 which is provided with a clutch member 31 at its lower end adapted to mesh with the clutch member 18 on the constantly running sleeve 5. This sleeve 30 is also loosely mounted on the main shaft.

A pin 33 on the part 2 supports a trigger 34, whose upper end is normally held outward by the spring 35. This pin also supports a forked arm 36, shown in plan in Fig. 10, having a slot 37 whose reduced end 38 is adapted to receive the reduced end 39 of a dog 40. This arm 36 and sleeve 30 are normally held up by the spring 41 but are pressed down to engage the clutch members 18 and 31 when the trigger 34 is pressed and held in. When the sleeve 30 and shaft 26 have made one rotation, the small cam 42 on the clutch member 31 strikes the lower end of the dog 40 and swings it into the larger portion of the slot 37, whereupon the spring 41 raises the arm 36 and disengages

the clutch members. When the trigger is released, the spring 35 presses it outward which carries the shoulder 43 on the dog above the forked arm 36 whereupon the 5 spring 41 swings the lower end 39 into the reduced portion 38 of the slot 37. The parts are now in position for the forming and driving of the next staple. For each staple to be driven, therefore, the operator presses 10 in the trigger and holds it so until he wishes to drive another staple, when he releases the trigger for an instant and then again presses it inwardly.

The upper end of the part 2 is formed 15 with a disk 45 on which may be mounted a shell 46. It also has a hub 47 to receive a spool for the wire 48 from which the staples are to be made, this spool being of any desired construction, preferably having a disk 20 49, a cylindrical drum 50 and arms 51 whose up-turned inner ends have ears 52 adapted to enter the groove 53 in the hub 47 and thus hold the spool rotatably in position, and a second disk 54. 25 On the part 1 is an inclined ridge 55 fitted with bushings 56 and 57 in which the feed shaft 58 is rotatably mounted. A lug 59 on this ridge is fitted with a bushing 60 which carries the shaft 61 of the idler roller 62 which engages with the roller 63 on the feed shaft 58. A bevel gear 64 on the feed shaft meshes with the teeth 65 on the mutilated gear 66 near the upper end of the main shaft 26 which thereby drives these rollers 30 35 a sufficient distance to feed a proper amount of the wire 48 to the staple forming device. A small case 67 may enclose these rollers which make one rotation for each staple and may be stopped at each rotation by a spring 40 45 whose outer end engages in a notch 69 in the roller 63 shown in Fig. 5.

The parts 1 and 2 are formed with 45 brackets 70 which support a guide plate 71 on which the shear member 72 is slidable between the guides 73 shown in cross section in Fig. 11. The wire 48 is fed across the front end of the shear member 72 by the rollers 62 and 63 which feed this wire in through a proper hole 85 in one of the 50 guides 73, as shown in Figs. 3, 11 and 15. The shear member is moved back and forth by an eccentric 74 on the main shaft 26, a connecting rod 75 and a pin 76 extending down from the shear member.

55 Extending up from the outer end of the guide plate 71 are two lugs 77 (Figs. 4, 12 and 15), which carry a pin 78 on which a dog 79 is mounted. See Fig. 13. The dog has outwardly extending arms 80 and has a 60 transverse groove 81 in the lower side of the inwardly extending tongue 82 to receive the staple wire. A spring 83 (Fig. 12) normally holds down this tongue 82, the width of which is slightly less than the width of 65 the guide groove 84 in the shear member

72 (Fig. 14). This spring is a coil of well known construction having one end extending to and resting on a lug 77 and the other end resting on an arm 80, but these details are omitted. The outer end of the guide 70 plate at the lugs 77 is built up level with the middle portion of the shear member, as shown in Fig. 4, so as to constitute a continuous slide-way for the staples.

While the staple wire is fed through the 75 hole 85 across the path of the shear member and across the space between the guides 73 and along the notch 81 in the dog 79, the shear member is near the rear end of its stroke. It then moves outward and shears 80 the staple wire and at the same time bends it so the ends of the staple lie at each side of the tongue 82 of the dog 79. During this time, the heavy spiral spring 87 at the upper end of the shaft is being tensioned. This 85 spring connects to the shaft 26 and to the crank pin 88 extending down from the crank 89, mounted on a short shaft 90 freely rotatable in the bushing 91 in the hub 47. A connecting rod 93 extends from the crank 90 pin 88 to the pin 94 on the hammer 95 which is slidable between the guides 96 on the shear member 72, that is, in the groove 84. The outward end of the hammer engages the inner end of the dog 79 at about the beginning 95 of the outward stroke of the shear member and of the hammer. As this dog prevents outward movement of the hammer, the spring 87 is tensioned during substantially one half of the rotation of the main 100 shaft and during nearly the entire shearing and bending operations of the shear member 72 and the dog 79. At the end of the outward movement of the shear member the inclined lugs 98 thereon engage under the 105 shoulders 97 on the dog and lift it. This is the position of the parts in Fig. 4. At this instant the released hammer 95 is driven outward by the spring 87 and pushes the staple A ahead of it along between the 110 guides 99 on the guide plate 70, these guides 99 being practically continuations of the guides 96 on the shear member between which the staple A is formed, the staple being forced entirely out of the tool by this 115 action of the hammer and into the article being worked on.

A shield 101 may be mounted over the shear member, the dog 79 and the hammer, being secured against the part 102 of the 120 case. While this staple forming and driving machine is especially adapted for fastening upholstering and other coverings for vehicles and furniture, its use is not limited thereto as it can be used for any other nailing and stapling where the amount of work is sufficient to warrant the necessary installation.

The details and proportions of the several 125 parts of this machine may all be changed 130

by those skilled in the art without departing from the spirit of my invention as set forth in the following claims.

I claim:—

- 5 1. In a staple forming and driving tool, a case adapted to be held in a hand of an operator and a guide therein, a shearing and bending member slidable in the guide, means for feeding wire thereto, a hammer to force the staple out of the tool, a shaft to control the operation of the hammer, a spring to actuate the hammer, and a main shaft to actuate the wire feeding means, the staple forming means and the hammer. 10 2. In a staple forming and driving tool, a case adapted to be held in a hand of an operator and a guide therein, a shearing and bending member slidable in the guide, means for feeding wire thereto, a hammer to force the staple out of the tool, a spring to actuate the hammer, a main shaft to actuate the wire feeding means, the staple forming means and the hammer, a shaft to transmit power to the tool, a manually controlled clutch to connect the power shaft to the main shaft and a lever operable by the fingers of the hand holding the tool to control said clutch. 15 3. In a staple forming and driving tool, a case adapted to be held in a hand of an operator and a guide therein, a shearing and bending member slidable in the guide, means for feeding wire thereto, a hammer to force the staple out of the tool, a spring to actuate the hammer, a main shaft to actuate the wire feeding means, the staple forming means and the hammer, a power shaft, a clutch to connect the power shaft to the main shaft, a manually operable trigger to move the clutch to operative position and a flexible shaft connected to said main shaft to rotate the same and permit the tool to be carried about. 20 4. In a staple forming and driving tool, a case adapted to be held in a hand of an operator and a guide therein, a shearing and bending member slidable in the guide, means for feeding wire thereto, a hammer to force the staple out of the tool, a spring to actuate the hammer, a main shaft to actuate the wire feeding means, the staple forming means and the hammer, a power shaft, a clutch to connect the power shaft to the main shaft, a manually operable trigger to move the clutch to operative position, and means to release the clutch at the end of one rotation of the main shaft. 25 5. In a staple forming and driving tool, a case adapted to be held in a hand of an operator and a guide therein, a shearing and bending member slidable in the guide, means for feeding wire thereto, a hammer to force the staple out of the tool, a spring to actuate the hammer, a main shaft to actuate the wire feeding means, the staple forming means and the hammer, a power shaft, a clutch to connect the power shaft to the main shaft, a manually operable trigger to move the clutch to operative position, and means to release the clutch at the end of one rotation of the main shaft. 30 6. In a tool for forming and driving fasteners, the combination of a case adapted to be held in a hand of an operator, a main shaft mounted therein, a guide plate, a fastener-forming device mounted thereon, a wire holding device, a pair of rolls to feed the wire to the fastener-forming device, a mutilated gear on the main shaft to actuate said rolls intermittently, and means to drive the finished fastener. 35 7. In a tool for forming and driving fasteners, the combination of a case adapted to be held in a hand of an operator, a main shaft therein, a wire-holding spool mounted on the end of the case co-axial with the main shaft and detachable from the case, a guide in said case, means to feed the wire across the guide, a shearing and forming member slidable in the guide, means connecting to the shaft to actuate said member, a hammer to drive the fastener, and resilient means connecting to the shaft and hammer whereby the hammer may be actuated. 40 8. In a staple forming and driving tool, the combination of a case, a main shaft therein, a wire-holding spool rotatable on the case, a feed shaft on the side of the case at an angle to the main shaft, gearing whereby the feed shaft is driven intermittently by the main shaft, an idler shaft mounted parallel to the feed shaft, feed rolls for the wire mounted on the feed shaft and idler shaft, staple shearing and forming means in the case and means connecting them to the main shaft, a hammer to drive the staples, and means to actuate the hammer. 45 9. In a staple forming and driving tool, the combination of a case and a guide plate therein, a shear member slidable in the guide plate, a hammer slidable on the shear member, means to positively actuate the shear member, resilient means to actuate the hammer, a dog on which the staples are bent, which dog is normally in the path of the hammer, and means on the shear member to move the dog to release the hammer after the staples are formed. 50 10. In a staple forming and driving tool, the combination of a case and a guide plate therein, a shear member slidable in the guide plate, a hammer slidable on the shear member, means to positively actuate the shear member, resilient means to actuate the

hammer, a dog on which the staples are bent, which dog is normally in the path of the hammer, and means on the shear member to move the dog to release the hammer after the staples are formed, said guide plate being formed with a pair of lugs between which the hammer may slide and on which said dog is pivoted.

11. In a staple forming and driving tool, 10 the combination of a case, a main shaft therein and formed with an eccentric, a guide plate, a shear member slidable on the plate, a connecting rod between said eccentric and the shear member, means to feed 15 staple wire through a hole in the guide plate into the path of the shear, a dog on which wire may be bent to form a staple, and staple-driving means resiliently connected to the shaft, said dog preventing the operation 20 of said driving means until moved out of the path thereof by said shear member.

12. In a staple forming and driving tool, the combination of a case, a main shaft therein and formed with an eccentric, a 25 guide plate, a shear member slidable on the plate, a connecting rod between said eccentric and the shear member, means to feed staple wire through a hole in the guide plate into the path of the shear, a dog on which 30 wire may be bent to form a staple, and staple-driving means resiliently connected to the shaft, and comprising a hammer 35 slideable on the shear member and a spring connected to the shaft to actuate the hammer.

13. In a staple forming and driving tool, 35 the combination of a case, a main shaft

therein and formed with an eccentric, a 40 guide plate, a shear member slidable on the plate, a connecting rod between said eccentric and the shear member, means to feed staple wire through a hole in the guide plate 45 into the path of the shear, a dog on which wire may be bent to form a staple, a clock-spring connected to the main shaft, a crank freely rotatable about the axis of the main shaft, a crank pin on the crank to which the spring is attached, a hammer for driving the staples slidable on the shear member, and a connecting rod between the 50 hammer and crank pin.

14. In a staple forming and driving tool, the combination of a case, a main shaft 55 therein and formed with an eccentric, a guide plate, a shear member slidable on the plate, a connecting rod between said eccentric and the shear member, means to feed staple wire through a hole in the guide plate into the path of the shear, a dog on which wire may be bent to form a staple, a clock-spring connected to the main shaft, a crank freely rotatable about the axis of the main shaft, a crank pin on the crank to which the spring is attached, a hammer for driving the staples slidable on the shear member, a connecting rod between the 60 hammer and crank pin, said dog being normally in the path of said hammer to hold it stationary while the staple is formed and the spring tensioned, and means on the shear member to move the dog out of the path of 65 the hammer.

PAUL RISSMAN.
